UNITED STATES PATENT OFFICE.

CHARLES SPRINGHORN, OF NEW YORK, N. Y.

MUSICAL INSTRUMENT.

Application filed September 14, 1922. Serial No. 588,169.

This invention relates to musical instruments and particularly to an improved mechanism adaptable to player pianos for playing automatically a combination of auxiliary musical instruments in accordance with predetermined conditions.

It is an object of the present invention to provide means for controlling expression devices employed in pianos.

Another object of the present invention is to cause a combination of musical instruments responsive to predetermined conditions, to be operated automatically, either independently or as a unit, in perfect time with the rhythm of the music as perforated in the ordinary music roll used in player pianos.

Another object is the provision of means whereby the introduction of the auxiliary musical instruments may be controlled manually.

A further object of the invention is the arrangement of the apparatus in an automatic player piano in a manner such that the introduction of the auxiliary musical instruments may be controlled automatically.

A still further object is to provide a simple, practical and efficient pneumatic action for controlling the effectiveness of the auxiliary musical instruments whereby a simple and compact construction results, which is accomplished in a simple and expeditious manner.

Other objects will appear hereinafter.

In accordance with the above and other objects, the present invention contemplates the provision of a plurality of auxiliary musical instruments, such as drums—both snare and bass—triangle, bird, tambourine, mandolin, stops and other such instruments which are arranged to be operated in perfect time with the rhythm of the music as determined by the cuttings in the music roll, i. e. the auxiliary musical instruments will function to produce music which is in perfect time with that being played on the piano. For controlling the operation of the musical instruments, both manually and automatically operated devices are provided which, through the instrumentality of a novel arrangement of valves, the application of air at the proper moment to the instrument desired is controlled. In the preferred form of the invention, a valve is arranged to be operated by twenty of the bass notes, preferably from the eighth to the twenty-eighth

note, while a similar valve is positioned in a manner such as to be operated by the treble notes, preferably from the thirty-seventh to the forty-ninth note. Experience has proven that such a combination results in superior operation giving a reproduction of music which is comparable with that produced by an orchestra of the highest grade. Each of the valves controlled by the piano action in turn controls the operation of primary and secondary valves which are individual to the respective musical instruments and which in turn control the introduction of air to act on mechanically operated devices for effecting the actuation of the musical instruments so selected.

Referring to the drawings.

Figure 1 illustrates a portion of a player action in cross-section, showing the arrangement of the mechanism for producing the desired result of the invention.

Figure 2 shows more in detail the valve mechanism and the manner of connections whereby the auxiliary musical instruments are operated in perfect time with the rhythm of the music being played.

Figure 3 illustrates diagrammatically the arrangement of the valves.

Figure 4 is a perspective of the valve mechanism which is operated by the allotted abstract bars of the piano action.

Figure 5 is a detailed view showing the allotment of the abstracts to the respective valve mechanisms.

Figure 6 is a perspective of the portion of the mechanism whereby the musical instruments selected will be operated until subsequently changed, due to the desire of the player.

Figure 7 illustrates the manner of connecting two musical instruments, which is the form best suited for what may be termed "house player pianos".

Figure 8 shows a portion of a music roll with the cuttings representing the various notes.

Figure 9 illustrates a modification of the arrangements shown in Figures 1 and 2.

In the drawing, like parts are represented by the same reference characters for the purpose of more easily tracing the operation of the respective mechanisms.

In Fig. 1 is shown a portion of an ordinary player piano, the base and other parts are shown in cross-section. 6 represents the supporting board of the piano with the

strings 7 suitably attached to the sound board as is common practice in pianos. The strings 7 are arranged to be operated by hammers 20 suitably pivoted at 22, through the action of pneumatic 9, which controls the operation of a lever 21. The pneumatic 9 is controlled by the introduction of air to a tube 14 extending from holes in tracker bar 13 over which the music roll 10 passes. The music roll 10 is wound on rolls 11 and 12, which are suitably journaled to the frame of the piano. Inasmuch as the player action per se does not form a part of the present invention, a detailed description thereof is considered unnecessary here as only so much of the piano mechanism is shown as is considered necessary for a clear understanding of the invention.

As is common practice, the piano is arranged to be operated either in accordance with the perforations in the music roll or manually through the operation of piano keys 8. Each of the keys is arranged through the instrumentality of a pin 17 Figs. 1 and 5 mounted in the free end thereof to engage an abstract 15. This abstract 15 is supported by a lever arrangement 18 which is connected to a block 19.

As shown in Fig. 5, twenty of the abstracts 30 of the left end portion are shown with pins 25 while at least eight of the abstracts on the right are shown with pins, the former being allotted to the bass notes, while the latter are common to the treble notes. Such an arrangement has proven to result in 35 superior operation giving a reproduction of music on the auxiliary musical instruments which is in perfect time with the rhythm of the music being played on the piano.

Each of the pins 25, which is secured to the abstracts 15, is arranged to operate a valve mechanism for causing the admittance of air to a series of tubes at atmospheric pressure. In the case of the pins allotted 45 to the bass notes, they are arranged in close proximity to the operating mechanism of the valve mechanism so that the valve will be maintained open when a series of the player actions in the range chosen are operated. When any one of the abstracts in this 50 particular section is operated and immediately followed by another, the valve is not allowed to close. This feature results from the particular location of the pins in the abstracts. Upon the operation of an abstract, the pin individual thereto engages the operating element of the valve and effects its opening. Now, should another abstract be immediately operated, its pin 55 will have engaged the operating element of the valve before it has traveled sufficiently far to effect its closure. However, in the case of the valve common to the treble notes the pins in the abstracts are positioned such 60 that should the player actions within the 65 range selected be operated, the valve will be opened and closed for each player action that is operated. Conversely from that of the valve allotted to the bass notes, the pins carried by the abstracts of the treble notes 70 will have moved downward a distance sufficient to allow the valve to close before the pin in another abstract engages the operating element of the valve. In this way, the valve will be opened and closed upon the 75 operation of each abstract notwithstanding the fact that they are operated in close succession. The latter feature produces the much desired staccato effect when drums are played as is so essential for orchestras. In 80 the case of short notes coming in the previously referred to range, the valve on the treble notes closes for each note. A different condition, however, exists when long notes are being played, that is, the music roll 85 is cut with a long note for one player action while it is also cut for a series of short notes in the same range. In the latter case, the valve will be held open as one of the player actions is maintained up resulting in a slurring action one to the other and causing only one beat. This feature is particularly illustrated in Fig. 8. As shown in the lower part of column A, the occurrence of a series 90 of notes in close succession will cause the maintenance of the particular valve open thus producing only one beat. This condition continues until the space appears between the notes as at "J" when the valve 95 will be closed.

As shown in Fig. 4, each of the valve mechanisms comprises a U-shaped plate 91 which has pivotally mounted in the upturned portions thereof, a bail 92 upon the straight portion of which is arranged an insulating medium 93. The insulating medium 93 is provided for reducing to a minimum the noise which might result due to the action of the pins 25 thereon. Rigidly fixed to the plate 91 is a plate 94 having at its free end thereof an aperture to which a tube connection 98 is connected. This member 94 has pivotally secured at 96 a member 95 which is also secured to the bail 92. Secured to the member 95 and in alignment with the aperture in the plate 94 is an insulating member 97 for insuring the closure of the aperture to the tube connection 98 when the bail 92 is in its lower-most position, or, in other words, when it is not actuated by a pin 25 due to the lifting of one of the abstracts 15.

In accordance with the present invention, means is provided whereby the introduction of the auxiliary musical instruments may be controlled either manually or automatically. In the former case, it is necessary to provide a series of buttons 4 which are arranged as shown in Figs. 2 and 3 along the front of the piano. In the latter case, it becomes 125 130

necessary to use a number of the lower and treble notes at the end of each end of the tracker bar 13, the number depending upon the number of auxiliary musical instruments which are desired to be operated.

When the latter arrangement is employed, it also becomes necessary to perforate the music roll with one small hole for each instrument whereby such perforations will, upon the movement of the music roll, be in perfect alignment with the holes in the tracker bar. For example, one hole may be allotted to the triangle, another to the tambourine, still another to the bird, and a fourth to the drum combination, etc. It is, of course, to be noted that it is not necessary to make a continuous series of perforations in order that the musical instruments will be operated in perfect time with the rhythm of the music being played as means is provided

whereby the instrument operated as determined by the actuation of one of the buttons or the fact that a perforation is brought into alignment with a hole in the tracker bar for causing the continuous playing of such instrument until subsequently changed due to the actuation of another button or the alignment of another perforation with a hole in the tracker bar.

As shown in Fig. 3, tube connections extend from the buttons 4 and the assigned holes in the tracker bar 13 to a common connection 50. From the common connection 50, a series of tube connections extend to a plurality of valves 51, 52, 53, 54, and 55, the number of such valves, of course, being determined by the number of musical instruments desired to be operated. Each of these valves 51 to 55 inclusive, controls the admission of air from a source to which an air line 28 is connected for operating a series of pneumatics 65, 66, 67, 68 and 69. Each of the pneumatics 65 to 69 inclusive is arranged with a pin 70 which, as shown more clearly in Fig. 6, is arranged to engage operating portions of a locking member 71. This locking member 71 is pivotally mounted to a pair of uprights 72 and 73 and is arranged upon being actuated by any one of the pins 70 to maintain such pin in the position determined by the actuation of the corresponding pneumatic until a subsequent selection.

Each of the pneumatics with the exception of pneumatic 65 controls the operation of a set of valves 80, 81, 82 and 83, Fig. 3, the construction of which will be more clearly described hereinafter. These valves 80 to 83 inclusive, control the actuation of a set of valves 100 to 107 inclusive. The valves 100 to 107 inclusive are connected with valves 45, 46, 47 and 48 in a manner for controlling the operation of a plurality of valves 125 to 136 inclusive. The valves 45 and 46 as shown in Fig. 3, are connected with valve 33 which is operated by the pins 25 on

the abstracts 15. The valves 47 and 48 on the other hand are connected by a tube 38 with valve 34 which is actuated by pins 25 connected to the abstracts on the left hand portion of the player action.

The valves 100 to 107 inclusive are arranged with the valves 125 to 136 inclusive in a manner such that these valves may be operated in combination. In order to cause the proper functioning of the valves 101, 103, 105 and 107, a check valve such as 108, 109, 110, and 111 is arranged independent to each of these valves and is controlled by the valves 45 and 46.

Extended from the valves 126, 127, 129, 131, 133 and 135 are tube connections which connect with bellows such as 146, 147 and 148 for controlling the operation of the auxiliary musical instruments such as 30, 31 and 32.

Referring to Figs. 2 and 3, the valves bearing reference characters 51 to 55 inclusive, comprise a block 59 which is of wood or other suitable material having openings therein which are arranged to be opened and closed by an operating member 56 of a valve 52. This operating member 56 has a portion extending to and in engagement with a pouch 58. Owing to a connection extending from a chamber in this valve to the air line 28, the pouch 58 is normally in the position shown in the drawing and the operating member 56 is in engagement with the seats 62 and 63. When the buttons 4 are in their normal unactuated position and no auxiliary perforations appear in the music roll 10, the pressure on the opposite sides of the pouch 58 is substantially equalized and accordingly is distended to the left. The equalization of pressure results from the location of the bleed hole 61 which is only a small hole approximately the size of a pin and which connects the chamber on the left hand side of the pouch 58 to the air suction line 28. Consequently, with both sides of the pouch 58 connected with the air suction line, the pressure on both sides of the pouch will be substantially equalized. The tip of the operating element 56 is mushroom shaped and obviously due to the air suction, will tend to move to the left but its movement is affected due to the application of air at atmospheric pressure on its back side and aided by the suction resulting from the air suction line 28. Now should either a button 4 be operated or an auxiliary perforation appear in the music roll 10, air at atmospheric pressure will be admitted to the connection 37. The connection 37 is

of a much larger cross section than the bleed hole 61, in which case the pressure on the two sides of the pouch 58 is no longer substantially equal and the pouch is caused to be distended to the right, carrying with it the operating element 56. Consequently, the

operating element 56 is caused to disengage seat 63 and engage seat 62. Upon the closure of the opening to connection 37, whether at one of the buttons 4 or an auxiliary perforation on the roll 10, pressure on the left hand side of the pouch is reduced and owing to the bleed hole 61 the pressure will be equalized shortly and the pouch 58 returned to the position shown in Fig. 2. The operating element 56 will follow the pouch upon the removal of the pressure applied thereto as previously described. With reference to the operation of this valve, it should be noted that the effective area of pouch 58 is considerably greater than that of the operating element 56. Inasmuch as this particular type of valve is a well known mechanism commonly employed in connection with pneumatics for pianos, further description is believed unnecessary. Leading from a chamber in the valve 52 is a passage 64 which connects with the pneumatic 66. The pneumatic 66 in turn controls the opening of valve 49 which, upon being opened, causes air to be admitted at atmospheric pressure to a chamber of valve 80. This valve 80, like the one previously described comprises an operating member 84 and a pouch 86 which is held normally in the position shown in the drawing due to the equalization of pressure existing on both sides of the pouch 58 when the valve 49 is closed which is produced by the air line 28. The operation of valve 80 is identical to valve 52 which has just been described. Arranged in operative relation with the valve 80 by means of an air passage 89 are valves 100 and 101. These valves are arranged with operating members 112 and 113 which have a coil spring connected with each other which normally holds the valves against their seats. Each of the valves 100 and 101 is connected with a check valve 108 and 155 which in turn are connected with the secondary valves 46, 48, which are controlled by the primary valves 45 and 47. The primary valve 47 is connected with valve 34 by a tube connection 38, while valve 45 is connected to valve 33 by a tube connection 39. Each of the valves 47 and 48 has operating members which, owing to the application of air to the pouches of each of these valves from the air suction line 28 are held in the position shown in the drawing. Extending from the valves 100 and 101 are tube connections 115 and 116, the former of these connections extends to the primary valves 125, which controls the operation of secondary valve 126. This secondary valve, as shown in Fig. 3, controls the admission of air to a tube connection 143 extending to bellows 147 which operates a tapper 152 for causing the operation of triangle 32. Tube connection 116 on the other hand extends from valve 100 to valve 128,

which controls secondary valve 127. When these valves 128 and 127 are operated, air is admitted to tube connection 153 extending from valve 127 to bellows 146 which controls the operation of the tambourine 31. It is thus apparent with such a set of connections that the tambourine and triangle will be operated together, the triangle being controlled from the bass notes or valve 34, while the tambourine is controlled by the treble notes or valve 33.

The operation of the mechanism previously described is as follows:

When one of the buttons 4, for instance, the second one from the left, as shown in the left hand corner of Fig. 3, is operated, valve 35 is likewise actuated for admitting air at atmospheric pressure to tube connection 36 which extends from valve 35 to the common connecting block 50, and thence through tube connection 37 to chamber 60 of valve 52. Valve 35 comprises a member 23 of thin metal which is rigidly secured at 24 by means of screws and carries a piece of insulating material 29 near its free end for insuring good contact between the aperture to which the tube connection 36 is connected. The admission of air to the chamber 60 which is at atmospheric pressure causes the operation of operating member 56 which thereupon disengages the seat 63 and engages the seat 62. The operation of the valve mechanism 52 in this manner now connects the passage 64 with the suction line 28 to the pneumatic 66. The pneumatic 66 is thereupon operated for causing the opening of valve 49 which will be maintained open so long as such condition exists owing to the engagement of pin 70 with the locking bar 71. The pin 70 and the pneumatic 66 will be held by locking bar 71 until a subsequent selection.

The opening of valve 49 admits air to one side of the pouch 86 of valve 80 thus owing to the bleed connection 87, which is arranged in a manner similar to that described in connection with valve 52, the pressure on the right hand side of the pouch 86 is increased whereby the operating element 84 of this valve is operated for disengaging the seat 85 and engaging the seat 88. The operation of this valve thereupon extends the suction line connected by tube 28 with the passage 89 extending to the valves 100 and 101.

Now when a series of notes are being played on the piano as determined by the perforations in the music roll, the abstracts 15, allotted to either the bass or treble notes, will be operated in accordance with the operation of the pneumatics 9 for opening and closing the valves 33 and 34 respectively, i. e. the bass notes effect the opening of valve 34 while the treble notes cause the corresponding action of valve 33. Valve 34, upon being opened, admits air at atmos-

pheric pressure to the tube 38 which extends from this valve to the lower chamber of valve 47. The air in the chamber 74 due to the admittance of air at atmospheric pressure is increased so that the operating element 43 is caused to disengage the seat 76 and engage the seat 79. The operation of this valve in this manner admits air to the lower chamber of valve 48 through the connection 90 whereupon the operating element 44 is lifted due to the increased pressure on the under side of the pouch 75. Normally both sides of the pouch individual to valve 48 are connected to the air suction line 28 and in consequence the pressure on both sides thereof is the same. However, upon the operation of valve 57, this equalization of pressure no longer exists. Operating element 44 will accordingly be lifted for admitting to connection 49 air at atmospheric pressure. The air supplied to the check valve 155 from the suction supply from which the connection 28 extends is cut off owing to the engagement of the operating element 44 of valve 48 with the seat 78. The disengagement of the operating element of this valve from seat 77 causes the admission of air to the check valve 155 at atmospheric pressure whereupon this check valve is operated.

Likewise, when valve 33 is operated by the pins secured in the abstracts of the treble notes, air is admitted to the tube connection 39 at atmospheric pressure whereupon valve 45 is operated for causing the operating element of this valve to disconnect the air line from the lower chamber of valve 46. The disconnection of the suction from the lower chamber of valve 46 increases the pressure on the underside of the pouch of this valve whereupon its operating element is lifted for disconnecting the air line from the check valve 108 of valve 101. Accordingly, valve 101 is operated in a manner similar to that described in connection with valve 100.

From the previous description, it is clearly apparent that the present invention provides a system of control whereby valves 100 and 101 are conditioned for operation, which are subsequently rendered effective due to the operation of the valves 34 and 33 through the instrumentality of the abstracts allotted to the bass and treble notes which in turn control the primary and secondary valves 45 to 48 inclusive.

Taking up the description from the point where it was dropped with reference to the admission of air from the tube connection 28 with the passage 89, the valves 100 and 101 are operated whereby air at atmospheric pressure is admitted to the tube connection 115, upon the operation of check valve 155 while air at a corresponding pressure is admitted to tube connection 116 upon the operation of valve 100. This latter check

valve is controlled by valves 45 and 46 which in turn are controlled by valve 33. The admission of air to the connection 115 at atmospheric pressure causes an increase in the air pressure on the under side of the pouch 140 of valve 125. The admission of air to chamber 139 of this valve causes the operating element 137 thereof to be lifted whereupon the suction from the tube connection 28 is cut off from the valve 126 and in place thereof air at atmospheric pressure is applied. Inasmuch as the air on the upper side of the pouch 142 of the valve 126 is connected with tube connection 28 and the other side thereof is connected to the air and since, the pressure on the underside of the pouch 142 is greater the operating element 138 is operated to disengage seat 145 and engage seat 144. The operation of this valve in this manner connects the tube 143 with the suction tube connection 28 extending from the air supply to the bellows 147 whereupon this bellows is operated for causing the corresponding actuation of the triangle 32.

From the previous description, it is apparent that the mechanism described permits of the operation of the triangle 32 in perfect time with the rhythm of the music roll as the valves 47 and to 48 inclusive serve to control the operation of the valve mechanisms 125 and 126 which control directly the operation of the musical instrument 32. From the arrangement shown in Fig. 3, it is apparent that when valves 101 and 108 are operated, air at atmospheric pressure is admitted to tube connection 116 which extends to valves 128 and 127 and accordingly bellows 146 will also be operated. The bellows 146 is arranged with an operating member for playing the tambourine. Such an arrangement makes it possible to operate both the triangle and tambourine in perfect time with the rhythm of the music on the music roll. It is to be noted here that the triangle 32 is controlled through the instrumentality of the valves 47, 48, 100, 125 and 126 by the valves 34 which is operated by the abstracts 15 of the bass notes. Also that the tambourine 31 is operated through the instrumentality of valves 45, 46, 101, 128 and 127 by valve 33 which is allotted to the treble notes.

Should it be desired to operate some of the other combinations of musical instruments, such as, for example, the bird combined with a set of drums (not shown) it would only be necessary to operate button 99 which, as in the previous case, operates a valve admitting air at atmospheric pressure to a tube connection to the common connecting block 50. From the common connecting block 50, the air traverses a second tube connection extending to valve 53. The operation of this valve, accordingly controls the release of the pin 70 of pneumatic 66 and operates pin 70 of pneumatic 67 to the

position shown in the drawing. The pin 70 in this case, will be held in the position shown by the locking bar 71 until a subsequent selection. The operation of the pneumatic 67 causes the operation of valve 81 which in turn conditions valves 102 and 103 for operation. When the abstracts allotted to valves 33 and 34 are operated, valves 45 and 47 are accordingly actuated for controlling the operation of secondary valves 46 and 48. These valves, like in the case just described, control the check valves 109 and 156. The operation of the check valves 109 and 156 causes the operation of valves 15 132 and 130. Likewise, valves 130 and 132 control the operation of valves 129 and 131. Valve 129 causes the admission of air from the suction line 28 to the tube connection 159 which extends from this valve to a pneumatic for operating a set of drums or other type of auxiliary musical instrument. The valve 131 on the other hand, controls the admission of air at atmospheric pressure to the tube connection 160, extending from this 25 valve to a bellows 148. The bellows 148 is connected to a second bellows 149 through a rigid operating connection 150. When the bellows 148 is operated, due to the operation of valve 131, the corresponding operation 30 of bellows 149 results which causes the introduction of air to the tube connection 151. This tube connection 151 extends to a mechanically operated bird 30, which responds to the actuation of the bellows 149 for producing harmonious music.

It is apparent from the description that the musical instrument may be operated in any combination desired, the operation of such instruments by means of the unique 40 method of control being operated in perfect time with the rhythm of the music cut in the music roll as it passes over the tracker bar 13.

The same operation will result when the 45 music roll 10 is perforated with a series of auxiliary perforations 160, 161 and 162 the number of such perforations depending upon the number of auxiliary musical instruments desired to be operated. As shown in Fig. 8, 50 five such perforations are cut to the left of the perforations which control the actuation of the abstracts 15, for producing music as perforated in the music roll. It is to be noted here that the auxiliary perforations 55 are not continuous but extend over a large area as it is not necessary in order to operate any one of the auxiliary musical instruments continuously to have the perforations cut continuously. This manner of operation is possible due to the arrangement of the pins 70 on the bellows 65 to 69 inclusive and the operating bar 71. When one of these auxiliary perforations passes over 60 a hole in the tracker bar 13, which is connected with the common connecting block 50

by a tube connection air at atmospheric pressure is admitted to a corresponding tube connection extending from the common block 50 to one of the valves, say 54. The operation of the mechanism from this point is identical to that previously described when one of the buttons is operated. As previously described when one of the buttons 4 is operated, air at atmospheric pressure is admitted to the tube connection and in consequence the associated valve is operated. In case of an auxiliary perforation appearing in the music roll 10, air at atmospheric pressure is admitted to the tube connection extending from the tracker bar 13 to the common block 50 and accordingly the particular valves 51 to 55 will be operated.

It is again to be noted that it is not necessary to continuously perforate the music roll in order to have this combination of instruments played in perfect time with the rhythm of the music as cut in the roll, as the bar 71 operated in a manner similar to that when one of the buttons 4 is operated for maintaining the condition until another perforation passes over a corresponding hole in the tracker bar 13. Such a perforation, in passing over another of the holes in the tracker bar, causes the operation of the corresponding valve with its pneumatic for releasing the previous selection and connecting in the other combination of instruments which will be operated in accordance with the operation of valves 33 and 34 which are operated by the abstracts of the bass and treble notes respectively.

In many cases, it is desired to discontinue the playing of the auxiliary musical instruments. In the present invention this is accomplished by providing a valve 51 which controls a pneumatic 65. The valve 51 is in turn controlled by the button and perforation on the extreme left as shown in Fig. 3. When either the button is operated or a perforation in the music roll is brought into alignment with a hole in the tracker bar 13, air at atmospheric pressure is applied to the valve 51 through the tube connection, extending from this valve to the common connecting block 50. The operation of valve 51 is identical with that previously described in connection with valve 52. Further description of the operation of the valve mechanism is therefore considered unnecessary here. Like in the operation of pneumatic 66, pneumatic 65 is operated when the valve 51 is operated. The operation of pneumatic 65 causes the movement of the pin 70 to the left whereupon the locking bar 71 is moved in a manner to affect the release of all other pins, restoring the system to normal.

Under certain conditions, it is only desired to operate a triangle and a bird. With these conditions, a large portion of the mechanism previously described can be dispensed

with. As shown in Fig. 7, the bellows for operating the triangle and the bird are connected by means of tube connections with the secondary valves corresponding to 126 and 127. These secondary valves, in turn, are controlled by primary valves 125 and 128. The previously enumerated valves are similar in construction to those described in detail in connection with the description pertaining to Fig. 2. Primary valves 125 and 128 are connected directly to valves 33 and 34 by means of tube connections. Valves 33 and 34 are controlled by the bass and treble notes respectively as in the previous case. Further description of the operation of this mechanism is considered unnecessary as a complete description of such operation was given in connection with the other mechanism.

In Figure 8, there is illustrated a portion of a music roll 10 showing the position of the perforations which control the operation of the abstracts of the piano action. In this figure, there is also shown broken lines indicating the range of the notes which have been selected for operating the bass and treble valves which results in superior operation of the system. The portion "A" represents the bass notes while "B" indicates the number of treble notes selected and the range in which the treble valve is effective. For the purpose of illustration, perforations 160, 161 and 162 are shown to the left of the music roll which are aligned with holes in the tracker bar 13 shown at "C." These perforations 160, 161 and 162 serve to operate the valve mechanism 52 and others of this series for controlling the introduction of the desired musical instrument. This brings out the point that it is unnecessary to have a continuous row of perforations in order to have the desired instrument continue to be operated. It is to be noted also that the same effect will be produced, as in the case of the perforations, if any of the buttons 4 positioned on the front of the piano are operated. Also, "D" indicates the section of the tracker bar which may also be utilized for controlling the introduction of various types of musical instruments. To the left of the music roll 10 is shown graphically at "E" the periods of operation of the instruments associated with the bass and treble valves. When the series of perforations 163 are brought into alignment with the corresponding hole in tracker bar 13, the valve 33 is operated for causing the operation of the other valves in a manner previously described for producing, in the case of a snare drum, what is usually referred to as a "snare roll." In this case, the valve 33 is maintained open during the series of perforations 163. Considering now the perforations designated by the numerals 164, a dif-

ferent condition exists as the perforations in this case are separated a distance sufficient to permit the valve 33 to open and close for each perforation. A staccato effect on the drum is thereby produced. By referring to the heavy lines on the left of Figure 8, a better understanding of the manner in which the valve operates may be obtained. In the case of the perforations 165, the valve 33 will be operated for each of such perforations as the position of the series 165, which operate this valve, is such that when two abstracts within the range "B" are operated, the valve will be opened and closed for each abstract, thus causing the valve mechanism controlling the action of the snare drum or other musical instrument which happens to be in operative connection to be operated for each note. With the arrangement of the notes in this manner the valve mechanism is operated for producing both the staccato and snare roll.

Referring now to the bass notes, which are in the range "A", in the case of a bass drum, a single beat is produced thereon to the point marked "J" where two beats are introduced to the point "K." Likewise, in the case of the perforations 122, two beats are produced which extends to the portion "L" of the music roll.

In the case of the valve 34, which is operated by the bass notes, this valve is opened and maintained open so long as the perforations continue, as distinguished from the action of the treble valve which opens and closes except when the perforations are close together as those in the series 163.

Although the above description pertains to the use of a snare and a bass drum, it is of course to be understood that other instruments may be introduced by the perforations 161 or 162 or even the operation of the buttons 4 to produce the same action and give a quality of music in accordance with the thoughts of the party who wrote the music.

Referring now to Figure 9, there is shown an arrangement of apparatus whereby the bass and treble valves are supplanted by mechanism operated by the same abstracts for operating contacts for controlling the operation of the auxiliary musical instruments. As in the previous figures, like parts are represented by like reference characters in order to make the examination of the apparatus easier. In this figure, the valves which are controlled through the action of the treble and bass valves 33 and 34 respectively and the valves under the control of the bellows 66 to 69 respectively are supplanted by switch contacts controlling electro-magnets which control through their armatures the introduction of air at atmospheric pressure to the primary valves 125, 128, 130, 132, 134 and 136. However, in

this case, in place of having valves controlled by the bellows 66 to 69, electric circuits are controlled thereby for conditioning for operation the electromagnets which are subsequently energized through the action of the treble and bass mechanism controlled notes.

Inasmuch as the operation of the valves 51 to 55 which control the operation of the bellows 66 to 69 has already been described in detail in connection with the other figures, further description of this part of the system as shown in Figure 9 is considered unnecessary here. If any one of the valves 52 to 55 inclusive is operated through either the alignment of a perforation in the music roll with a hole 3 in the tracker bar 13, or the operation of one of the buttons 4, the corresponding bellows is operated. As in the previous case, the bellows so operated is arranged to be held in operative condition through the instrumentality of the locking bar 71 until a subsequent selection. The bellows control contacts which have connections extending therefrom to contacts controlled by the mechanism operated by the treble and bass notes and the windings of the respective electromagnets. In the case of the bellows 66, contacts 176 and 177 are operated for conditioning an energizing circuit for magnets 170 and 175.

Also the mechanism 183 and 184 controlled by treble and bass notes in place of controlling the introduction of air control the actuation of contacts 166 and 167. When the contacts 176 and 177 are operated and the contacts 166 and 167 also operated, an energizing circuit is established for each of the magnets 170 and 175. The circuit for the magnet 170 may be traced from the positive terminal of the battery 168, contact 167, contact 177, and the winding of the electromagnet 170 to the other terminal of the battery 168. Likewise, the magnet 175 is energized over a circuit which can be traced similarly. The magnets 170 and 175, upon being energized, causes the admission of air to the tube connections 115 and 116 at atmospheric pressure to the primary valves 125 and 128. These valves in turn control the secondary valves 126 and 127 which control the operation of bellows 146 and 147. In the case of the operation of bellows 146, the tambourine 31 is operated, while for the bellows 147, the operating element 152 is moved to a position where the triangle 32 is operated.

In the case of the other bellows 67, 68 and 69, corresponding contacts such as 178, 179, 180 and 181 are operated for likewise controlling the energization of electromagnets 171, 172, 173 and 174. These magnets are also controlled through the action of the treble and bass notes which are in the ranges "A" and "B" as shown in Figure 8.

It is also to be noted that the operating element of 183 is positioned such that when two abstracts 15 are operated in the range "B" sequentially, the contacts 166 will be actuated for the operation of each abstract thus producing the desired effect on the associated musical instrument. The accomplishment of this particular feature results from the location of the pins in the abstracts 15 with respect to the operating bail of the associated valve. As previously described, these pins are located so that upon the operation of each abstract allotted to the range "B" the associated valve will be caused to open and close. When an abstract is operated, its pin engages the operating bail of the valve and causes the valve to be opened. Upon the operation of another abstract immediately following the previously operated abstract, the pin carried by the latter operating abstract will not have engaged the operating bail of the brush before its closure, in which case the valve will be opened and closed for the operation of each abstract. For further details of this particular part of the mechanism, reference should be had to the description previously given with respect to this particular operation. In all other respects the operation of the system is identical with that described in connection with the pneumatically operated type of system.

Although the invention has been described in connection with a particular arrangement of piano mechanism, it is, of course, obvious that other variations may be made without departing from the spirit and scope of the present invention.

The invention claimed is:

1. In combination, a piano action, manual keys and pneumatics for operating said piano action, a plurality of auxiliary musical instruments, mechanism controlled independently of said manual keys and pneumatics for conditioning said auxiliary musical instruments for operation, and means operated by the piano action in response to the operation of either said keys or pneumatics for causing the actuation of the particular auxiliary musical instrument previously conditioned by the operation of said mechanism.

2. In combination, a piano action controlled by the perforations in a music sheet, a plurality of auxiliary musical instruments, pneumatically operated mechanism actuated independently of the music note perforation in said music sheet for conditioning said instruments for operation, and means operated subsequently in accordance with the music note perforations in said sheet for causing the operation of the conditioned musical instruments in accordance with the operation of the piano action.

3. In combination, a piano action controlled by the perforations in a music sheet,

- a plurality of auxiliary musical instruments, mechanism controlled independently of the music note perforations in said music sheet for controlling the introduction of the musical instruments either separately or in combination, and means operated in accordance with the note perforations in said music sheet for actuating said piano action and for causing the operation of the auxiliary musical instruments introduced through the operation of said mechanism. 5
4. In combination, piano actions controlled either manually or automatically by note perforations in a music sheet, a plurality of auxiliary musical instruments, mechanism for conditioning said instruments for operation either separately or in combinations, a valve common to a plurality of said piano actions and controlled thereby for causing the actuation of the conditioned auxiliary instruments. 10
5. In combination, piano actions controlled either manually or automatically by note perforations in a music sheet, a plurality of auxiliary musical instruments, mechanism for conditioning said instruments for operation either separately or in combinations, a pair of valves, each of said valves being common to a different group 15 of said piano actions and operated by any one of the actions in the respective groups for causing the actuation of the conditioned musical instrument. 20
6. In combination, piano actions controlled either manually or automatically by note perforations in a music sheet, a plurality of auxiliary musical instruments, mechanism for conditioning said instruments for operation either separately or in combinations, a pair of valves, each of said valves being common to a different group 25 of said piano actions, and means associated with said piano actions and responsive to the operation thereof for opening and closing said valves whereby the conditioned musical instruments are operated in accordance with the operation of said piano actions. 30
7. In combination, piano actions controlled either manually or automatically by note perforations in a music sheet, a plurality of auxiliary musical instruments, mechanism for conditioning said instruments for operation either separately or in combinations, a pair of valves, each of said 35 valves being common to a different group of said piano actions and disposed with respect to said valves to cause them to be operated differently upon the successive actuation of a plurality of piano actions in said groups whereby the conditioned musical instruments are operated in accordance with the operation of said piano actions. 40
8. In combination, piano actions controlled by the perforations in a music sheet, a plurality of auxiliary musical instruments, 45
- mechanism for selecting the musical instruments either singly or in combination for operation previously to the operation of said piano actions, and means operated simultaneously with the actuation of the piano action in accordance with the perforations in the music sheet for causing the operation of the selected auxiliary musical instrument as determined by said mechanism. 50
9. In combination, piano actions controlled by the perforations in a music sheet, a plurality of auxiliary musical instruments, mechanism for selecting the musical instruments either singly or in combination for operation previously to the operation of said piano actions, means operated by any one of a predetermined group of the piano actions in accordance with the perforations in the music sheet for causing the operation of the selected auxiliary musical instrument 55
- as determined by said mechanism. 75
10. In combination, piano actions controlled by the perforations in a music sheet, a plurality of auxiliary musical instruments, mechanism for selecting the musical instruments either singly or in combination for operation previously to the operation of said piano actions, means operated by any one of a predetermined group of the piano actions in accordance with the perforations in the music sheet for causing the operation of the selected auxiliary musical instrument 60
- as determined by said mechanism, and means for maintaining the selected auxiliary musical instrument operatively associated with 100 said second recited means until a subsequent selection. 90
11. In combination, piano actions controlled by the perforations in a music sheet, a plurality of auxiliary musical instruments, mechanism for selecting the musical instruments either singly or in combination for operation previously to the operation of said piano actions, a pair of valves individual to different predetermined groups of piano actions and operated by any one of the piano actions in the respective groups for causing the operation of the selected auxiliary musical instrument. 105
12. In combination, piano actions controlled either manually by keys or automatically by note perforations in a music roll, a plurality of auxiliary musical instruments, an auxiliary series of perforations in the music roll, means controlled by said auxiliary perforations independently of the note perforations for rendering said auxiliary musical instruments effective, and mechanism operated in accordance with the note perforations in the music roll for controlling the actuation of the instruments thus effected. 115
13. In combination, piano actions controlled either manually by keys or automatically by note perforations in a music roll, a 120
- 125
- 130

- plurality of auxiliary musical instruments, an auxiliary series of perforations in the music roll, means controlled by said auxiliary perforations independently of the note 5 perforations for rendering said auxiliary musical instruments effective, mechanism operated in accordance with the note perforations in the music roll for controlling the actuation of the instruments thus 10 effected, means for locking said first recited means in an operated condition, and mechanism also responsive to an auxiliary perforation in the music sheet for rendering said locking means ineffective.
- 15 14. In combination, piano actions, means controlled by the note perforations in a music roll for operating the piano actions, a plurality of auxiliary musical instruments, manually controlled means controlling the 20 introduction of such instruments, and means operated by any one of a group of predetermined piano actions for simultaneously causing the operation of the musical instrument selected through the operation of said manually controlled means.
15. In an automatic player piano, the combination of a plurality of auxiliary musical instruments, the method of operating such musical instruments consisting in conditioning 30 said auxiliary musical instruments for operation, and subsequently causing their operation upon the actuation of any one of a group of predetermined piano actions whereby the conditioned auxiliary musical instruments are operated in perfect time with 35 rhythm of the music being played by the piano notes.
16. In an automatic player piano, the combination of a plurality of auxiliary musical instruments, the method of operating such musical instruments consisting in conditioning said auxiliary musical instruments for operation, and subsequently causing their operation upon the actuation of any one of a group of predetermined piano actions included in the bass and treble notes.
17. In combination, piano actions, a plurality of auxiliary musical instruments, devices for selecting said instruments for subsequent operation in different combinations or separately, means operated by any one of a group of predetermined piano actions for controlling the operation of the selected auxiliary musical instrument, and mechanism controlled jointly by said devices and said means for operating said musical instrument in accordance with the operation of the piano actions.
18. In combination, piano actions, means controlled by the perforations in a music roll for operating the piano actions, a plurality of auxiliary musical instruments, manually operated means for controlling the introduction of such instruments independently of said piano action operating 60 means, and means operated in accordance with the operation of the piano actions for causing the operation of musical instruments.
19. In combination, piano actions, means controlled by the perforations in a music roll for operating the piano actions, a plurality of auxiliary musical instruments, manually operated means for controlling the introduction of such instruments independently of said piano action operating means, and means comprising a valve operated upon the actuation of any one of a plurality of said piano actions, and pneumatics controlled by said valve for causing the operation of said selected auxiliary musical instrument. 70
20. In combination, piano actions, means controlled by the perforations in a music roll for operating the piano actions, a plurality of auxiliary musical instruments, manually operated means for controlling the introduction of such instruments independently of said piano action operating means, means comprising a valve opened and closed upon the successive operation of piano actions in a predetermined group thereof, and means responsive to said valve for operating the selected musical instruments. 80
21. In combination, piano actions, means controlled by the perforations in a music roll for operating the piano actions, a plurality of auxiliary musical instruments, manually operated means for controlling the introduction of such instruments independently of said piano action operating means, means comprising a pair of valves, each of said valves being common to different groups of said piano actions, mechanism for opening and closing one of said valves upon the successive operation of the piano actions individual thereto, mechanism for maintaining said other valve open upon successive operation of the piano actions, individual thereto, and means controlled by said valves for causing the operation of the selected auxiliary musical instrument. 90
22. In combination, a plurality of piano actions, means for operating said actions, a pair of valves operated upon the actuation of any one of a plurality of the piano actions, a plurality of musical instruments, mechanism controlling the introduction of the auxiliary musical instruments, and means operated directly by said mechanism and operating jointly with said valve for operating the selected auxiliary musical instruments in accordance with the operation of the piano actions. 100
23. In combination, a plurality of piano actions, pneumatic devices, and a valve controlled by any one of a predetermined number of the piano actions for causing the operation of said pneumatic devices. 110

24. In combination, a plurality of piano actions, pneumatic devices, and a valve controlled by any one of a predetermined number of the bass piano actions for causing the operation of said pneumatic devices.
25. In combination, a plurality of piano actions, a pair of valves controlled by any one of a predetermined number of the bass piano actions, the other by any one of a predetermined number of the treble actions, a plurality of musical instruments, and means responsive to the operation of said valves for causing the operation of the auxiliary musical instruments.
26. In combination, a plurality of abstracts controlled either manually or automatically by the perforations in a music roll, a plurality of musical instruments, means for selecting said instruments for operation, a plurality of devices common to predetermined ones of said abstracts, and means mounted on said abstracts and spaced at different distances from said devices for causing their operation differently to effect the actuation of the selected instruments.
27. In combination, a plurality of abstracts controlled either manually or automatically by the perforations in a music roll, a plurality of musical instruments, means for selecting said instruments for operation, a valve individual to predetermined ones of the abstracts and pins secured to the abstracts and arranged to cause the opening and closure of said valves upon the operation of each abstract to effect the actuation of the selected instruments.
28. In combination, a plurality of abstracts controlled either manually or automatically by the perforations in a music roll, a plurality of musical instruments, means for selecting said instruments for operation, a valve individual to predetermined ones of the abstracts and pins secured to the abstracts and arranged to hold the valve open upon the sequential operation of the abstracts for effecting the actuation of the selected instruments.

In witness whereof, I hereunto subscribe my name this 9th day of Sept., A. D., 1922.

CHARLES SPRINGHORN.
